Primary Examiner — Kevin Rudzinski*Assistant Examiner* — Kathleen Jones(74) *Attorney, Agent, or Firm* — Stoel Rives LLP; Robert R. Teel(57) **CLAIM**

We claim the ornamental design for a bezel for a sighting device, as shown and described.

DESCRIPTION

FIG. 1 is an isometric view showing a bezel for a sighting device.

FIG. 2 is a front elevation view of the bezel.

FIG. 3 is a left side elevation view of the bezel.

FIG. 4 is a right side elevation view of the bezel.

FIG. 5 is a top plan view of the bezel; and,

FIG. 6 is a bottom plan view of the bezel.

In the drawing figures, the broken lines are illustrative of environmental structure that forms no part of the claimed design.
